CLOSURE WITH A TEAR STRIP OPENER

Ermal C. Fraze, 355 W. Stroop Road, Dayton, Ohio

Filed Aug. 21, 1963, Ser. No. 76,316

Term of patent 14 years

(Cl. D58—26)

I claim:

The ornamental design for a closure with a tear strip opener, as shown.
